UNITED STATES PATENT OFFICE.

THOMAS O'TOOLE, OF WESTVILLE, ILLINOIS.

POWER-HAMMER DIE.

1,279,751

Specification of Letters Patent. Patented Sept. 24, 1918.

Application filed February 7, 1918. Serial No. 215,757.

To all whom it may concern:

Be it known that I, THOMAS O'TOOLE, a citizen of the United States, and resident of Westville, in the county of Vermilion and State of Illinois, have invented certain new and useful Improvements in Power-Hammer Dies, of which the following is a specification.

My invention relates to the construction of the dies for steam, trip or similar power hammers having opposed, relatively movable dies, and more particularly to the construction of the opposite or coacting working faces of such dies.

One object of this invention is the provision of top and bottom dies having coacting working faces of novel construction and having improved means whereby the forging and cutting operations are facilitated in making forgings with such hammers.

Another object of this invention is to provide a hammer die having an integral cutting edge by which metal is severed, and having means adapted to prevent upsetting and consequent dulling of the so-formed cutting edge by impact of an opposed hammer die.

A further object of the invention is to provide power hammer dies having working faces of novel construction adapted to simplify the forging and cutting operations in making mining machine bits or cutters.

A still further object of my invention is the provision of coacting hammer dies having the novel constructions, arrangements and combination of parts shown in the drawings, to be hereinafter described in detail, and to be particularly pointed out in the appended claims.

Referring now to the drawings, forming part of this specification, Figure 1 is an isometric plan, showing the upper or working face of the anvil or bottom die of a power hammer embodying the novel features of my invention.

Fig. 2 is a sectional end elevation of the die of Fig. 1, in the plane of the line II-II of Fig. 1.

Fig. 3 is a sectional end elevation, similar to that of Fig. 2, the section being taken in the plane of the line III-III of Fig. 1.

Fig. 4 is an inverted isometric plan, showing the lower or working face of the vertically movable top or hammer die of a power hammer, as constructed and arranged in accordance with this invention, the die being

shown inverted in order to illustrate clearly the working face of the hammer die.

Fig. 5 is a sectional end elevation of the top or hammer die, in the plane of the line V-V of Fig. 4.

Fig. 6 is a sectional end elevation, similar to that of Fig. 5, the section being taken in the plane of the line VI-VI of Fig. 4.

Fig. 7 is a plan showing one form of mining machine pick or cutter, in the making of which dies embodying my invention as shown and described are particularly adapted for use.

In the accompanying drawings, the anvil or bottom die as a whole, is designated by A, and the coacting relatively movable top or hammer die by B.

The bottom die A is provided on each side, adjacent to its bottom 2, with notches 3, 3, which extend longitudinally so as to form a dovetail tongue 4 by which the stationary or fixed die A is removably secured in place on a suitable base or foundation. The top die B also is provided with a notch 5 on each side to form a dovetail tongue 6 adjacent to its face 7, by which the die B is removably secured to the lower end of the vertically reciprocable piston rod of a steam or other power hammer.

Dies embodying the novel features forming my invention, being applicable to power hammers of any of the various old and well known types, a hammer is not illustrated nor described.

The upper or working face of the anvil die A has an intermediate portion 8 and end portions 9, 9, which are in the same flat horizontal plane, the middle section 8 being separated from the end section 9, 9, by transverse slots or grooves 10, 10. The grooves 10 have vertical side surfaces 11, 11, defining the width of the groove and inclined bottom surfaces 12 and 13, these inclined surfaces converging upwardly and intersecting to form an integral cutting edge 14 which is in the plane of the horizontal working faces 8 and 9 of the die.

When subjected to continuous use for any considerable time interval the dies become highly heated and when the plane forging faces are at one end the cutting edges on another end of the dies the dies are not uniformly heated. By providing a pair of the transverse grooves 10 two cutting edges are obtained and the plane forging surface is thereby located in the middle of the length

of the die, or in line with the vertical center of the hammer where the maximum blow is obtained.

By alternately using the cutting edges formed by the converging surfaces of the grooves 10 and by using the plane flat die surface located between the grooves 10 for the major portion of the forging operations, the dies are uniformly heated, which greatly lessens liability of breakage and increases the life of the dies. It will be readily seen that by having the sloping bottom surfaces 12 and 13 of these grooves intersect in the plane of the top or working surface of the die, upsetting of the cutting edge or edges 14 by impact of the vertically movable hammer die B, is avoided and prevented in using the hammer dies.

The intermediate portion 8 of the die A has a beveled surface 15 which connects the horizontal upper surface 8 with the vertical side surface 16 on the front or smith's side of the die. (See Figs. 1 and 3).

The working surface 17 of the upper or hammer die B also is flat and in the same horizontal plane, except for a small portion 18 thereof which is beveled, and which inclines inwardly from the front or smith's side 19 of this die to a point between the side surfaces of the die. The ends 20, 20 of this beveled portion 18 also are beveled (as is clearly shown in Figs. 4 and 5).

In securing the hammer die B, shown and described, to the piston rod of the hammer, the end 21 of this die will be placed adjacent to the end 22 of the bottom or anvil die A, and, of course, the side surfaces 16 and 19 will both be on the front or smith's side of the hammer.

Ordinarily the working faces 8 and 9 and inclined surfaces 12 and 13 of the die A and working faces 17, 18 of the die B, will be accurately machined before being put into use, and it will be readily seen that when necessary these faces may be re-machined so as to restore them after long use makes such step necessary or desirable.

In the use of hammer dies constructed as shown and described herein, the beveled surface 15 and inclined surface 18 of the two dies coact in the forging operations so as to prevent the metal being forged from "kicking" out or backwardly when the metal being forged is struck a blow by the top die, and by providing the beveled forging face 18 on the lower surface of the die B, the forming of the bent, sharpened or cutting end 21 of picks or cutters C, such as that shown in Fig. 7, is readily accomplished.

The inclined bottom surfaces 12 of the transverse slots or grooves 10 in the work-

ing face of the bottom die or anvil A may be utilized in some of the forging or forming operations. For example, in forming picks like that shown in Fig. 7, the point of the bent end 24 of the pick C will be provided with a sharp cutting edge 23 which is forged thereon, in the manner shown in Fig. 2, the face 17 of the upper die B coacting with the inclined face 12 and cutting edge 14 of the die A in producing the sharp cutting edge, and in this way making it unnecessary to later sharpen the pick by filing or grinding to complete the pick.

The advantages of my invention will be appreciated by those skilled in the art.

Modifications in the construction and arrangement of parts forming the working faces of the dies may be made without departing from my invention. The integral cutting edges may be formed at an end or the ends of the die, and other changes may be made within the scope of the appended claims.

I claim:—

1. In a power hammer, a die having a flat working face, said die having a transverse groove therein, and the bottom surfaces of said groove being oppositely inclined and intersecting to form an integral cutting edge, with the cutting edge in the plane of the flat upper surfaces of said die, at opposite ends of said cutting edge.

2. In a power hammer, a die having a flat working face, said die having a plurality of transverse grooves therein with the bottom surfaces of said grooves inclined upwardly and inwardly, and the inclined surfaces of said grooves intersecting to form integral cutting edges in the plane of the flat upper surfaces of said die.

3. In a power hammer, an anvil die and coacting hammer die having flat working faces, the working face of one of said dies having transverse grooves therein, and the bottoms of said transverse grooves being inclined relatively to the flat working face of said die to form an integral cutting edge, and the grooves in the working face of the grooved die being opposite flat portions of the working face of the other die.

4. In a power hammer, a stationary anvil die and an opposite hammer die having flat working faces, said anvil die having a transverse groove in its working face and said groove having upwardly and inwardly converging bottom surfaces intersecting to form an integral cutting edge and said edge being in the plane of the flat working-surfaces of the die.

In testimony whereof I have hereunto set my hand.

THOMAS O'TOOLE.
